CHRISTOPHER EHLINGER, OF WATERLOO, IOWA, ASSIGNOR TO BRADFORD BRUCE HUNTER, OF WATERLOO, IOWA.

FURNACE.

1,084,321.

Specification of Letters Patent.

Patented Jan. 13, 1914.

Application filed March 10, 1913. Serial No. 753,274.

To all whom it may concern:

Be it known that I, CHRISTOPHER EHLINGER, a citizen of the United States of America, and a resident of Waterloo, Black-hawk county, Iowa, have invented certain new and useful Improvements in Furnaces, of which the following is a specification.

My invention relates to improvements in furnaces, and the object of my improvement 10 is to supply for hot-air furnaces, a simple, inexpensive and effectively working hood adapted to equally divide the rising heated air to deliver it to the several flues leading to the delivery registers. These objects I 15 have accomplished by the means which are hereinafter described and claimed, and which are illustrated in the accompanying drawings, in which:

Figure 1 is an elevation of a jacketed hot- 20 air furnace of the usual type, supplied with my improved distributing-hood, parts of the latter being broken away. Fig. 2 is a plan view of said distributing-hood. Fig. 3 is an enlarged longitudinal vertical section of 25 one of the distributing-segments or funnels of said hood and its adjustable joint or collar-connection for a flue.

Similar numerals and characters of reference denote corresponding parts throughout 30 the several views.

My improved hot-air furnace hood is formed of a plurality of like funnel-shaped segments 1. As shown best in Fig. 3, each hollow segment is truncated obliquely to 35 furnish a circular port 5 with outer wall vertical and upper part having a gradual slope downwardly at *b* to a central point *c* at which point all the converging inner parts of said segments are radially directed, so as 40 to locate said point of meeting at *c* lower than the level of said port and nearly as low as the lower circular edge of the hood formed by the joined vertical walls *a* of the segments.

45 Referring now to said Fig. 1, it will be seen that the lower circular edge of said hood is secured within the part 8 of the top of the cylindrical casing 6, which latter is in the usual way spaced from an inclosed 50 furnace 7, the latter indicated by dotted lines only, said furnace being adapted to heat the air in the interspace between it in its casing, the heated air then rising as indicated by the arrows to pass upwardly into 55 said hood above the furnace. Since the con-

vergence-point *c* of the hood-segments 1 is located near the top of the inclosed furnace, while the funnel-shaped segments of the hood radiate therefrom divergently upwardly in every direction, since the segments 60 are equal in dimensions, it is evident that the heated air will not be able to create cross- or interfering-currents within the hood, but as soon as received within the hood the whole body of heated air is simultaneously 65 divided into equal portions or streams which are diverted by the sloping parts *b* of the segments into the ports 5, to pass thence into communicating flues not here shown. Since it will be desirable in many cases to so adapt 70 the hood as to permit it to deliver to flues which are variously inclined thereto, I have provided in combination with said segments adjustable collars 2, being short cylinders having one end cut slantingly as shown and 75 then spread at a bead 3 to fit over a narrow outwardly-flanged rim 4, on the segment about the port 5. Obviously, when said collar is rotated it will rock into different inclinations relative to said hood, as is shown in 80 Fig. 1 in two instances, where two collars are placed differently, one being horizontal, the other vertical, though in intermediate positions such collars may be inclined at different slopes to the horizontal or vertical as 85 desired.

The hood may be formed of one piece or of joined segments, and may be easily fitted on any furnace-casing.

Having described my invention, what I 90 claim as new, and desire to secure by Letters Patent, is:

1. A furnace dome, comprising a radially crimped hollow body having outer depending parts united to form a rim connection 95 for the upper end of a spaced outer casing of hot-air furnace, the outer parts of the dome between the crimps being higher than those near its center, and said outer parts having outwardly-opening obliquely-directed outlet-ports, the crimps forming heated-air outlet-funnels converging inwardly and directed downwardly to a common point lower than the level of their delivery-outlets, and movable collars seated 105 about said ports adjustable to vary their angles relative to said dome.

2. A furnace dome, adapted to be connected to a spaced furnace-casing, comprising hollow frusta obliquely-truncated to 110

provide exit-ports and conjoined to radiate from a common depressed center, and crimped to form hot-air funnels, and obliquely-directed flue-connections movably seated about said exit-ports and adapted to be moved to vary their angles of inclination relative to said dome.

3. A furnace dome, comprising a radially crimped hollow body, having outer depending parts united to form a rim-connection for the upper end of a spaced outer casing of a hot-air furnace, the outer parts of the dome between the crimps being higher than

those near its center, and said outer parts having outwardly-opening outlet-ports, the 15 crimps forming heated-air outlet-funnels converging inwardly and directed downwardly to a common point lower than the level of their delivery-outlets.

Signed at Waterloo, Iowa, this 20th day 20 of Feb., 1913.

CHRISTOPHER EHLINGER.
